HANDLE FOR PLUMBING FITTINGS

Lloyd K. Jones and Martin W. Downey, Morgantown, W. Va., assignors to Rockwell Manufacturing Company, Pittsburgh, Pa.

Original design application Oct. 30, 1970, Ser. No. 25,742. Divided and this application Jan. 13, 1972, Ser. No. 217,713

Term of patent 14 years

Int. Cl. D23—01
U.S. Cl. D23—29

FIG. 1

FIG. 2

FIG. 3

FIG. 1 is a top plan view of a handle for plumbing fittings embodying our new design;

FIG. 2 is a side elevational view thereof; and

FIG. 3 is a bottom plan view thereof.

This is a division of design application Ser. No. D. 25,742, filed Oct. 30, 1970.

We claim:

The ornamental design for a handle for plumbing fittings, substantially as shown.
